UNITED STATES PATENT OFFICE.

PATTERSON G. FENNY, OF GORHAM, MAINE.

FOOT-REST.

SPECIFICATION forming part of Letters Patent No. 269,780, dated December 26, 1882.

Application filed November 3, 1881. Renewed November 15, 1882. (No model.)

To all whom it may concern:

Be it known that I, PATTERSON G. FENNY, of Gorham, in the county of Cumberland and State of Maine, have invented certain new and useful Improvements in Foot-Rests; and I do hereby declare that the following is a full, clear, and exact description of the invention, which will enable others skilled in the art to which it appertains to make and use the same, reference being had to the accompanying drawings, and to letters of reference marked thereon, which form a part of this specification.

My invention relates to improvements in foot-rests; and it consists in an adaptation of the various parts to produce an adjustable rest suited to any of the positions required by the varying postures of the body of a person reclining at ease. I attain this by the mechanism illustrated in the following drawings, in

which—

Figure 1 is a side view. Fig. 2 is in part a vertical section. Fig. 3 is an end view.

A is the top, on which the feet and legs of a person are to be supported. B B are two legs or supports. C is the base.

In the construction of my device any suitable frame of wood may be made for the top A, and in the drawings I represent one of a length of about two feet and about twice its width.

At the lower end is a fender or foot-board, a, of a few inches in height, against which the feet may push for the purpose of preventing the person from sliding down from his chair when lying in an extended position, as in sleep.

At the other end of the top A, I place a few coiled-wire springs, b, supported upon a strip of wood or canvas, c, which is extended between the ends of the side pieces of the top A. Over the upper surface of the top A any

suitable cushion or covering may be placed—such as hair-cloth. The purpose of the springs b is to make an easy and pliant ending to the foot-rest, so that at that portion of the leg which comes across this ending there shall be

avoided the usual effect of a sharp and rigid line or edge, cutting or pressing into the muscles and interfering with the circulation of the blood. I also aid the springs in accomplishing this by giving a rounded termination to

the side pieces of the foot-rest, as seen at d in Figs. 1 and 2. Upon the under side of the

top A, I fasten the two legs B, one on each side of the frame, and in the middle lengthwise. These legs B are each attached at their upper ends to the top A by means of a hinge, 55 which permits the top A to be inclined forward or backward and be placed at any desired angle with respect to the legs B B. These hinges are marked e e. The top A is held fixed at the desired angle, as to the legs B B, by 60 means of the curved rods f f and thumb-screws g g. These rods f f are rigidly attached at their ends to the under side of the top A, and run through the legs B B freely when the thumb-screws g g are loosened. The legs B B 65 are extensible telescopically, and capable of being held at any desired length by joints and thumb-screws. These telescopic joints are seen at h h, and these thumb-screws are marked i i. The legs B B are also at the bottom placed 70 on hinges moving in a plane lengthwise with the top A. These hinges are marked j j. Upon the hinges j j the legs B B can be moved forward and backward, carrying the top A with them. The legs B B are held in their 75 motion upon these hinges j j at any desired angle with the base C by means of the curved rods k k and thumb-screws l l. The base C is made in any appropriate manner to give a firm support to my device in the various positions 80 required for its use.

It will be easy to see that my invention accomplishes the adjustment of a foot-rest to all the varying positions of a person sitting in a chair by means of the two sets of hinges and 85 the telescopic joint. The joint h determines the height of the rest from the floor. The hinges j j enable one to place the legs B B of the foot-rest at that angle to the floor which the position chosen by a person requires, in order 90 to bring the weight or the pull which is caused by holding the feet and legs into a direction on the legs B B that will best prevent the foot-rest from tipping over. The legs B B, when the weight is thus brought into their direction, 95 operate as a brace against the tendency to tip, which manifests itself when the supporting-legs B B are in the perpendicular. The hinges e e enable the sitting person to bring the cushion or upper surface of the top A into a direction parallel with the proposed extension of the legs and enable him to obtain a uniform 100

bearing on all parts. This twofold adjustment spoken of, by means of the two sets of hinges, is a noticeable feature of my invention.

Another method of use of my device is obtained by means of the two sets of hinges. By leaving loose the thumb-screws *ll* and *gg* a person sitting in a rocking-chair can while rocking support his feet upon my foot-rest.

Having thus described my invention, what I claim as new, and desire to secure by Letters Patent of the United States, is—

The combination, in a foot-rest, of the foot-board *a* on the top *A*, the wire springs *b* on the inner edge of the said top, the support *c*, the rounded side pieces, *d*, the hinges *ee* of the

top *A*, the curved rods *ff*, and thumb-screws *gg*, to hold said top, the telescopic joints *hh* and thumb-screws *ii*, and the hinges *jj* of the legs *B* *B*, curved rods *kk*, and thumb-screws *ll*, to hold the legs *B* *B* at any desired angle ²⁰ on their hinges, all as and for the purposes herein set forth.

In testimony that I claim the foregoing as my own I affix my signature in presence of two witnesses.

PATTERSON G. FENNY.
